(57) **CLAIM**

The ornamental design for a paver stone, as shown and described.

DESCRIPTION

FIG. 1 is a perspective view of a paver stone according to an embodiment of the present invention;

FIG. 2 is a bottom plan view of the paver stone shown in FIG. 1;

FIG. 3 is a top view of the paver stone shown in FIG. 1;

FIG. 4 is a front elevational view of the paver stone shown in FIG. 1;

FIG. 5 is a rear elevational view of the paver stone shown in FIG. 1;

FIG. 6 is a side elevational view of the paver stone shown in FIG. 1, as viewed from the right in FIG. 1;

FIG. 7 is a side elevational view of the paver stone shown in FIG. 1, as viewed from the left in FIG. 1;

FIG. 8 is a top view of the paver stone shown in FIG. 1 set in a pattern with the broken lines being directed to environment and are for illustrative purposes only and the broken lines forming no part of the claimed design;

FIG. 9 is a perspective view of a paver stone according to a second embodiment of the present invention

FIG. 10 is a top view of the paver stone shown in FIG. 9; FIG. 11 is a bottom view of the paver stone shown in FIG. 9;

FIG. 12 is a front elevational view of the paver stone shown in FIG. 9;

FIG. 13 is a rear elevational view of the paver stone shown in FIG. 9;

FIG. 14 is a side elevational view of the paver stone shown in FIG. 9, as viewed from the right in FIG. 9;

FIG. 15 is a side elevational view of the paver stone shown in FIG. 9, as viewed from the left in FIG. 9; and,

FIG. 16 is a top view of the paver stone shown in FIG. 9 set in a pattern with the broken lines being directed to environment and are for illustrative purposes only and the broken lines forming no part of the claimed design.
